DOUBLE ROLLING ATTACHMENT FOR
PRINTING PRESSES

David S. Harnly, Jr., Scottdale, Pa.

Application June 14, 1949, Serial No. 98,906

8 Claims. (Cl. 271—56)

1

This invention relates to printing presses and press feeders and, in particular, to a double rolling attachment for conventional presses and press feeders.

Most of the modern presses are operatively connected up and synchronized with an automatic stock or sheet feeder, the feeder functioning to separate a new sheet from the stock pile, pick it up, and deliver it to a conveyor on which it is carried to the transfer cylinder of the press. This cylinder is provided with grippers to secure the sheet thereon and, in most forms, the cylinder is oscillated to deliver the sheet to an impression cylinder beneath which a type-bearing frame is reciprocated. To print a sheet, the impression cylinder is moved downwardly by eccentric mechanism, into a position in which the sheet will contact the type as it moves beneath it, this lower position being subsequently referred to as the printing position of the impression cylinder.

The particular presses and feeders for which the invention is adapted operate generally in the manner described above, and in addition, they utilize what is known as a pneumatic feed which includes suction devices to pick up the sheets and, sometimes, compressed air nozzles to separate the sheets one from the other. The suction as well as the compression is controlled by rotary valve mechanism which includes a rotary cylinder mounted in a valve casing, the cylinder being provided with a plurality of openings arranged to register with openings in the casing. Flexible tubing communicates the suction caps and compressed air nozzles with the casing openings, so that, as the valve cylinder rotates, the various registrations effect the described feed.

In printing certain forms, it often becomes desirable to resort to what is known as double rolling, which, briefly, is the skipping of one feed on alternate reciprocations of the type-carrying frame, the object being to obtain a better distribution of ink by passing the type twice under the inking rolls for each printing operation. In printing an ordinary page of words, or the like, such double rolling is not necessary, but, when it is desired to print solid forms that require extra heavy ink covering, or for slip-sheeting or interleaving, the printing is greatly improved by double rolling. If not used, it often happens that the printed sheet shows a "ghosting" of type over the solid portion, or there may be objectionable roller streaks. Presses and feeders of this type are constructed so as to permit this double rolling, but none, so far as I am aware, permits a fully automatic double rolling. Stated in the other way, it appears that these presses and feeders re-

2

quire the presence of an operator during the double rolling, his job being to throw a lever or perform some other manual job to prevent one sheet being fed during alternate reciprocation of the type-carrying frame. Of course, such manual operation not only is objectionable in that it requires the constant attention of the operator, but also it may result in faulty work if the operator is not skilled and careful.

Another characteristic of most modern printing presses is that they are so constructed that when a sheet is not fed to the transfer cylinder, or when a sheet becomes crumpled on the feeder conveyor, an automatic detector is brought into action to shut down the whole operation of the machine and prevent a jamming-up of the sheets which might very easily ruin functional parts of the press. These sheet "Detectors," as they are commonly known, are arranged so that they may be rendered inoperative by manually turning a knob when double rolling is being performed, this being done to prevent the machine from turning off when a sheet is not fed. However, there remains the obvious danger of a jamming-up of the sheet when the detector is turned off, or, as more frequently happens, an operator may forget to re-set the knob to the "on" position after double rolling is completed.

It is therefore among the objects of this invention to provide apparatus for controlling the operation of automatic presses of the type described above so as to effect an automatic double rolling, as well as mechanism which permits the crumpled sheet detector to be left "on" during the automatic double rolling.

Other objects are to provide mechanism in accordance with the above objects which is unusually simple, inexpensive and easily mounted on the press as well as being perfectly reliable in operation.

The preferred embodiment of the invention is illustrated in the accompanying drawings of which Fig. 1 is a somewhat diagrammatic side elevation of a printing press of the type described with the apparatus of this invention operatively mounted thereon; Fig. 2 an enlarged plan view of pneumatic sheet feeding mechanism of the press showing the manner in which the double rolling apparatus of the invention is mounted; Figs. 3 and 4 views taken along lines III—III and IV—IV, respectively, of Fig. 2; and Fig. 5 an enlarged view showing a portion of the sheet detector control apparatus forming a part of the invention.

Before describing the particular apparatus which forms the subject matter of this invention, it is believed best to describe, by reference to the

drawings, the structure and operation of a particular press and feeder for which the apparatus is suited. However, it should be understood that the invention is not limited to this particular press and feeder since, as will be appreciated by those acquainted with this art, there are a number of other presses and feeders capable of employing the teachings to be set forth. Also, subsequent use of the term "press" is intended to include broadly the printing, as well as the feeding, mechanism.

Referring to the drawings, and in particular to Fig. 1, the stock of sheets to be printed are carried on a tray 1 which is vertically reciprocable in frame 2 of the "feeder" mechanism of the press. The sheets, one at a time, are picked up from the pile and delivered to a conveyor 3 by pneumatic mechanism that includes a group of swingable suction caps 4 (Fig. 2) and another group of compressed air nozzles 6, these pneumatic devices being controlled by valve mechanism, which, as shown, includes valve cylinder 7, (Fig. 4) provided with a plurality of holes adapted to register with other openings provided in a cylinder casing 8. Flexible tubing 9 connects casing 8 with the feeding members 4 and 6, and the casing, also, is connected to suitable suction and compressed air pumps, this latter connection being through parallel tubular shafts 10 and 11. Also, as seen, the cylinder has a knob portion 12 extending out through the end wall of the casing, the principal purpose of the knob being to permit the cylinder to be withdrawn from the casing for cleaning. In operation, rotation of the valve cylinder communicates the feeding elements with their pneumatic sources, the sequence of the communications being arranged to produce the desired sheet feeding.

After the sheets to be printed are deposited on feeder conveyor 3, they are carried to a transfer cylinder 13 (Fig. 1) that is equipped with suitable gripper fingers (not shown) that hold the sheet to the cylinder. Usually, the sheets are carried on conveyor 3 by an endless tape which, in turn, is mounted on a shaft 14 operatively connected by a chain 15 to another shaft 16, this latter shaft being mechanically connected to the main drive of the press. Proceeding with the printing cycle, transfer cylinder 13 functions to deliver sheets to an impression cylinder 17 which is a constantly rotating member and, for this purpose, the transfer cylinder usually is oscillated in a timed relationship with the rotation of the impression cylinder 17 so that the sheet is delivered by the transfer cylinder into suitable gripping fingers of the impression cylinder. The actual printing is done by passing a type-carrying frame 20 beneath the impression cylinder, this frame being reciprocated horizontally of the press from a position near the feeder to a position near an ink fountain 18 on the opposite side of the impression cylinder and then back towards the feeder. As stated, impression cylinder 17 normally is carried a spaced distance above the type, but to print, it is moved downwardly, upon oscillation of the transfer cylinder, so as to contact the type as it passes beneath it. The ink for the type is provided by inking fountain 18 and inking rolls 19, also, are used to break up the ink and cause an even distribution of the ink upon the type.

In front of and directly adjacent to fountain 18 are a series of inking rolls 19 and special mechanism (not shown) is provided so that ink is fed to the rolls and consequently to the type

only when the impression cylinder is moved downwardly into its printing position. The net result is that if no sheet is delivered to the transfer cylinder then the impression cylinder is not moved into printing position and, also, ink is not fed to the inking rollers.

Concerning double rolling most presses are constructed in such a way that an operator can manually double roll when desired. In the particular press shown this is accomplished by rotatably mounting collars 21 and 22 (Fig. 3) on suction and compressed air tubes 10 and 11, and, by providing these tubes and the collars with openings 23, 23a and 24, 24a, the openings of the collars being so arranged as to be capable of being swung into registry with openings 23 and 24 of the tubes by rotating the collars. Obviously, when such a registry is effected, the suction and compressed air tubes both are vented to atmosphere and no pneumatic power is supplied to the suction caps and air nozzles to produce a sheet feeding. Consequently, when the operator desired to double roll, he simply rotates collars 21 and 22 to vent the pneumatic lines. To facilitate such operation, the two collars are connected together by means of cross bar 26 fitted into grooves provided in the bottom of the collars and loosely secured therein by pins 28, 28a and a hand lever 27 is mounted on one of the collars, the swinging of the lever producing the desired collar rotation.

One of the important features of the present invention is to provide apparatus which will dispense with the operator required to manually throw lever 27, and, also, to insure a proper double rolling. Referring to the drawings, and, particularly to Fig. 4, this apparatus includes a horizontal, transversely extending shaft 31 provided with a collar 32 of a proper diameter to fit tightly over knob 12, this knob being the portion of rotary valve cylinder 7 which extends outwardly through the end wall of valve casing 8. Consequently, shaft 31 is rotatably driven by the rotary motion of valve cylinder 7. Centrally of shaft 31, it is supported by any suitable means such as a bearing plate 33 that is mounted on suction and compressed air conduits 10 and 11 and clamped in position by means of clamps 34. Outwardly of bearing plate 33, a pair of clutch discs 36 and 37 are mounted on the shaft, disc 36 being keyed to the shaft for rotary movement with it. The clutch discs are detachably engaged by means of a retractable plunger 38 carried by a pin 39 secured to and projecting outwardly from disc 37. The arrangement of the disc connecting mechanism is conventional and, of course other suitable arrangements may be used. Briefly, that shown includes a coil spring 41 compressed between shoulders formed on the plunger and within the pin, the spring acting to press the end of the plunger into an opening 42 provided for it in disc 36. To allow the plunger to enter opening 42, pin 39 is provided with radial slots to receive lugs 43 formed in the knob of plunger 38. To disengage the members plunger 38 simply is retracted against the spring pressure and then turned sufficiently to prevent its lugs from entering the slots of the pin.

To effect the automatic double rolling, pin 39 is so positioned on disc 37 that, during the rotation of the disc, the pin will contact lever 27 of collar 21 and swing both collars arcuately a sufficient amount to align openings 23, 23a and 24, 24a. As stated above, when this occurs, there is no sheet feeding due to the fact that both

the suction and the compressed air tubes are vented to atmosphere. To reduce friction as pin 39 rides over lever 27, the pin is provided with a freely rotatable ring 44.

Also, it will be appreciated that once the lever has been depressed in the manner described and the suction and compressed air tubes vented, it is necessary to return the collars to a position in which the venting openings are not aligned, so that pneumatic power will be supplied to the suction caps and compressed air nozzles. Referring to Figs. 2 and 3, this is accomplished by means of a coil spring 46 mounted in such a way that movement of collars 21, 22 and cross bar 26, produced by pin 39, compresses the spring, while, after pin 39 has ridden over lever 27, the spring exerts pressure to return the collars to normal, non-venting position. As shown, this return mechanism includes an arm 47, secured to the press frame and provided with a pair of brackets 48 and 49 which support a reciprocable plunger arm 51. The plunger arm mounts a shoe 52 which constantly bears against cross bar 26, and spring 46 is compressed between bracket 49 and a shoulder 53 rigidly carried by the plunger. Thus, positive movement of collar 26 to the right (Fig. 3) compresses the spring, the compression causing bar 26 to return to its normal position when no positive force is acting on the bar, or, in other words, on the collars 21 and 22. To prevent abrupt and jarring movement of the collars, it is desirable to mount a leaf spring 57 on lever 27, this leaf spring gradually allowing the collars to return to their normal position as pin 39 rides over it.

Summarizing this double rolling operation, it will be noted that, in one clockwise 360° revolution of valve cylinder 7, as well as discs 36, 37 and pin 39, there, normally, would be two sheet feedings, but, since the collar movement described vents the pneumatic lines, once during the revolution, only one feed results. Of course, the arrangement must be such that, at this particular interval during which the pneumatic lines are vented, the rotating valve, normally, would effect a feed due to registration of the openings in the valve cylinder and casing. Consequently, during each 360° revolution of the disc, one of the normal feeds is eliminated, or, in other words, the press is double rolling for each single sheet fed to it. However, if desired, the same result would be accomplished simply by positioning the collar openings to align with the air tube openings when the collars are moved to their retracted angular position by spring 46, which, in this instance, would be a tension instead of a compression spring. In such a case, the retracted position would be the venting, or non-feed, position and pin 39 would function to move the collars to a non-venting, or feeding, position. Also, it will be appreciated that the arrangement described is adapted for the particular press shown, which feeds twice during each valve cylinder rotation. In other presses, it may be necessary to make some minor mechanical rearrangements depending upon the operation of the particular valve mechanism employed.

A further feature of the invention is an attachment which automatically prevents the crumpled sheet detector from shutting down the whole operation of the press when the double rolling mechanism described is operating. As has been pointed out, these presses are provided with mechanism which operates in such a way that, if the sheet to be printed crumples before

it reaches transfer cylinder 13, or, if a sheet feeding is not effected, the transfer cylinder does not oscillate. Further, the failure of the transfer cylinder to oscillate sets in motion mechanism which shuts down the whole machine. Such sheet detectors normally are arranged in such a way that the moving of a knob to an "on" position (Fig. 1) sets the machine so that it will be shut down, while turning of the knob to an "off" position so sets the machine that it will not be shut down regardless of the presence of crumpled sheets or the failure of a sheet to be delivered.

In the present apparatus, mechanism is provided which, at the particular time in which the double rolling mechanism described above eliminates one of the normal feeds, the sheet detector is turned to an "off" position and the failure of the sheet to be delivered does not shut down the operation of the press. Referring to Figs. 1 and 5, this mechanism includes a small gear 61 that is keyed onto the end of shaft 16, which, as explained above, is the shaft from which the drive for the endless tape of feeder conveyor 3 is taken. However, gear 61 could be keyed to any other constantly-moving member of the press. Meshed with gear 61 is another larger reduction gear 62 which is rotatably mounted on another shaft 63 extending outwardly from the side wall of the feeder frame. Further, shaft 63 is keyed to a cam 64 that, in turn, bears against the end of a longitudinally extending rod 66 which, at various intervals, is supported by means of rollers 67. At the opposite end of rod 66, it is provided with a downwardly projecting lug 68 (Fig. 1) which bears against a rack bar 69. The rack bar, in turn meshes with a pinion 71 which is substituted for the usual knob by which the sheet detector mechanism is turned on or off. Beyond pinion 71 the end of rack bar 69 is drilled to receive another rod 73 which mounts a collar 74 and a compression spring 76 is disposed between the collar and the end of the rack bar. Consequently, as shaft 16 rotates, cam 64 forces rod 66 and rack bar 69 to the left and turns pinion 71. As the rotation proceeds the configuration of the cam allows rack bar 69 to return to its normal position, and the force for returning it is provided by compression spring 76. The arrangement, or in other words, the configuration of cam 64, is such that, at the time in which the failure of a sheet to be delivered to transfer cylinder 11, due to double rolling normally would shut down the operation of the machine, the pinion wheel is turned to such a position that the sheet detector mechanism is turned "off." Consequently, the failure of the sheet to be delivered does not effect a shut down of the machine. Immediately after that timed interval and during the period in which a sheet is being fed to the transfer cylinder, spring 76 acts to return pinion 71 to its "on" position so that the sheet detector is capable of detecting crumpled sheets and preventing jamming of sheets in the machine. It will be appreciated that such sheet-detector controlling mechanism is unnecessary when the press is single rolling, and, to eliminate its operation, the driving connection between cam 64 and pinion 71 can be broken by removing lugs 68.

Having described the apparatus of the invention and the presses for which it can be used to advantage, it now should be appreciated that the invention provides unusually simple and reliable apparatus for automatically carrying out a double rolling printing operation, and, at the same

time, apparatus which automatically controls, where necessary, the sheet-detecting mechanism and the presses so as to completely eliminate any need for intervention by an operator during the double rolling.

According to the provisions of the patent statutes, I have explained the principles, preferred embodiment and mode of operation of my invention, and have illustrated and described what I now consider to represent its best embodiment. However, I desire to have it understood that, within the scope of the appended claims, the invention may be practiced otherwise than as specifically illustrated and described.

I claim:

1. In a pneumatically fed printing press having at least one pneumatic conduit leading from a source of pneumatic pressure to a sheet feeder of the press and having a constantly rotating valve disposed in said conduit for communicating the feeder with said source, apparatus for automatically effecting double rolling comprising a collar rotatably mounted on said conduit, disengageable driving connections between said valve and said collar, said connection rotating with the valve and including a cam disposed to contact and rotate the collar once during each rotation of the valve, said collar and conduit being provided with openings arranged to align upon said intermittent collar rotation to vent said pneumatic pressure and eliminate one of the sheet feedings normally effected by said valve rotation, and means for returning said collar to non-venting position.

2. In a pneumatically fed printing press having suction and compressed air conduits leading from sources of pneumatic pressure to a constantly rotating valve and a plurality of flexible air lines leading from said valve to suction and compressed air feeders, said air lines being brought into communication with said conduits during each rotation of the valve, apparatus for automatically effecting double rolling comprising a collar rotatably mounted on each of said conduits, means connecting said collars together for causing them to move in unison, a lever arm projecting radially outward from one of said collars, a shaft secured at one end to said valve for rotation with it and extending therefrom to a position near said arm, a disc keyed to the free end of said shaft, a second disc detachably engaged for rotation with said first disc, a cam arm extending outwardly from said second disc for engaging and rotating said lever arm and collar once during each rotation of the valve, said collars and conduits each being provided with openings arranged to align upon said collar rotation to vent said pneumatic pressure and eliminate one of the sheet feedings normally effected by said valve rotation, and means for returning said collars to non-venting position.

3. In a pneumatically fed printing press provided with manually-controlled missing and crumpled sheet detecting mechanism and having at least one pneumatic conduit leading from a source of pneumatic pressure to a sheet feeder of the press and a constantly rotated valve disposed in the conduit for communicating the feeder with said source, the combination of apparatus for automatically effecting double rolling comprising a collar plate movably mounted on said conduit, driving connections between said valve and said plate for intermittently moving the plate, said plate and conduit being provided with openings arranged to align upon said intermittent

movements to vent said pneumatic pressure and eliminate one of the sheet feedings normally effected by said valve rotation, and means for returning said collar to non-venting position; and apparatus for automatically shutting off said sheet-detecting mechanism during said double rolling comprising a reciprocable arm connected at one end to said manual control of said detector, arm-reciprocating means synchronized with the operation of said sheet feeder for moving said arm in one direction a sufficient amount to shut off said detector when said one feed is eliminated by said double rolling apparatus, and means for returning said arm to its normal position for turning on said detector when a sheet is being fed.

4. In a pneumatically fed printing press provided with manually-controlled missing and crumpled sheet detecting mechanism and having at least one pneumatic conduit leading from a source of pneumatic pressure to a sheet feeder of the press and a constantly rotated valve disposed in the conduit for communicating the feeder with said source, the combination of apparatus for automatically effecting double rolling comprising a collar plate movably mounted on said conduit, driving connections between said valve and said plate for intermittently moving the plate, said plate and conduit being provided with openings arranged to align upon said intermittent movements to vent said pneumatic pressure and eliminate one of the sheet feedings normally effected by said valve rotation, and means for returning said collar to non-venting position; and apparatus for automatically shutting off said sheet-detecting mechanism during said double rolling comprising a pinion keyed onto said manual control of the detector, a rack bar meshed with said pinion, rack bar driving means synchronized with the operation of said sheet feeder for moving said rack bar in one direction a sufficient amount to shut off said detector when said one feed is eliminated by said double rolling apparatus, and means for returning said arm to its normal position for turning on said detector when a sheet is being fed.

5. In a pneumatically fed printing press provided with manually-controlled missing and crumpled sheet detecting mechanism and having at least one pneumatic conduit leading from a source of pneumatic pressure to a sheet feeder of the press and a constantly rotated valve disposed in the conduit for communicating the feeder with said source, the combination of apparatus for automatically effecting double rolling comprising a collar rotatably mounted on said conduit, driving connections between said valve and said collar for intermittently rotating the collar, said collar and conduit being provided with openings arranged to align upon said intermittent rotations to vent said pneumatic pressure and eliminate one of the sheet feedings normally effected by said valve rotation, and means for returning said collar to non-venting position; and apparatus for automatically shutting off said sheet-detecting mechanism during said double rolling comprising a reciprocable arm connected at one end to said manual control of said detector, arm-reciprocating means synchronized with the operation of said sheet feeder for moving said arm in one direction a sufficient amount to shut off said detector when said one feed is eliminated by said double rolling apparatus, and means for returning said arm to

its normal position for turning on said detector when a sheet is being fed.

6. In a pneumatically fed printing press provided with manually-controlled missing and crumpled sheet detecting mechanism and having at least one pneumatic conduit leading from a source of pneumatic pressure to a sheet feeder of the press and a constantly rotated valve disposed in the conduit for communicating the feeder with said source, the combination of apparatus for automatically effecting double rolling comprising a collar rotatably mounted on said conduit, driving connections between said valve and said collar for intermittently rotating the collar, said collar and conduit being provided with openings arranged to align upon said intermittent rotations to vent said pneumatic pressure and eliminate one of the sheet feedings normally effected by said valve rotation, and means for returning said collar to non-venting position; and apparatus for automatically shutting off said sheet-detecting mechanism during said double rolling comprising a pinion keyed onto said manual control of the detector, a rack bar meshed with said pinion, rack bar driving means synchronized with the operation of said sheet feeder for moving said rack bar in one direction a sufficient amount to shut off said detector when said one feed is eliminated by said double rolling apparatus, and means for returning said arm to its normal position for turning on said detector when a sheet is being fed.

7. In a pneumatically fed printing press having at least one pneumatic conduit leading from a source of pneumatic pressure to a sheet feeder of the press and having a constantly rotating valve disposed in said conduit for communicating the feeder with said source, apparatus for automatically effecting double rolling comprising a collar rotatably mounted on said conduit, disengageable driving connections between said valve and said collar, said connection rotating with the valve and including a cam disposed to contact and rotate the collar once during each rotation of the valve, and means for returning said col-

lars after said cam rotation, said collars and conduits each being provided with openings arranged to align and vent said pneumatic pressure when said collars are in said returned position whereby a sheet feeding is effected by said collar rotations once during each valve rotation.

8. In a pneumatically fed printing press having suction and compressed air conduits leading from sources of pneumatic pressure to a constantly rotating valve and a plurality of flexible air lines leading from said valve to suction and compressed air feeders, said air lines being brought into communication with said conduits during each rotation of the valve, apparatus for automatically effecting double rolling comprising a collar rotatably mounted on each of said conduits, means connecting said collars together for causing them to move in unison, a lever arm projecting radially outward from one of said collars, a shaft secured at one end to said valve for rotation with it and extending therefrom to a position near said arm, a disc keyed to the free end of said shaft, a second disc detachably engaged for rotation with said first disc, a cam arm extending outwardly from said second disc for engaging and rotating said lever arm and collar once during each rotation of the valve, and means for returning said collars after said cam rotation, said collars and conduits each being provided with openings arranged to align and vent said pneumatic pressure when said collars are in said returned position whereby a sheet feeding is effected by said collar rotations once during each valve rotation.
